UNITED STATES PATENT OFFICE.

SAMUEL LIPSIUS, OF NEW YORK, N. Y.

RAISED-PRINTING PROCESS AND PRODUCT.

1,146,182.

Specification of Letters Patent. Patented July 13, 1915.

No Drawing.

Application filed November 25, 1914. Serial No. 873,946.

To all whom it may concern:

Be it known that I, SAMUEL LIPSIUS, a citizen of the United States, and residing at New York, in the county of New York 5 and State of New York, have invented a new and Improved Raised-Printing Process and Product, of which the following specification is a full disclosure.

This invention relates to the printing of 10 characters in simulation of the raised effects produced by the action of dies or engraved plates and ordinarily known as embossing work.

Various methods have heretofore been 15 proposed and to some extent put into commercial use whereby embossed work may be simulated by acting in conjunction with an ordinary printing press, and without necessitating the manufacture of special dies. In 20 practising these well known methods, ordinary stiff, quick-drying printers' ink is first impressed upon a sheet of paper, a quantity of fusible resinous powder (such as gum elemi) is then deposited on the freshly inked 25 surface and, by carefully melting this powder, it is caused to amalgamate with the inked surface so that when cold it will give a raised surface imitating the relief effects yielded by a die. This process has, however, 30 possessed many heretofore unavoidable difficulties which have materially contributed to reduce the commercial value of the process. One difficulty with this imitation embossing, 35 as heretofore practised, lies in the fact that the finished work has a very strong tendency to peel or strip on the paper so that, when the paper is folded or creased, the 40 raised material will crack and flake, and the detached particles thereof will not only give the appearance of loose dirt scattered over the paper and collected in the folds 45 thereof, but the neat effect of the printing itself is also lost. This has deprived this process of the very point on which its commercial utility depends; *i. e.*, a neatness and beauty comparable with die work.

Now one object within the contemplation 50 of this invention is to create an improved process such as will yield a sheet of paper having printed characters not only closely imitating embossing but also so flexible and so tenaciously adhering to the paper that it may be folded without unduly cracking or

flaking, so that the letter-heads on high grade bond paper may be folded or handled 55 severely without a depreciation in appearance.

Another object is to render commercially available at a comparatively low cost a sheet of paper having raised characters characterized 60 by a materially greater degree of flexibility than those produced by former methods and characterized by a tenacity of adhesion to the paper which will enable them to remain intact on the paper notwithstanding 65 considerable rough handling and folding.

Another object of this invention is to discover mutually compatible materials and the manner of utilizing the same, whereby the ultimate composition of the raised character 70 will possess a considerable amount of elasticity or flexibility combined with a strong tenacity for the paper so that the resultant printed matter may be given more durability. 75

A still further object is to create a method whereby, immediately after leaving the final or hardening step, the raised printing will acquire a durable status on the paper so that the latter may at once be folded or handled 80 without fear of producing flaking or the like.

Other objects will be indicated in connection with the following analysis of this invention which consists in the materials, the 85 unique relations of the ingredients, the relative proportioning thereof, the method of combining the same, and the resultant article of manufacture, all as more completely outlined herein. 90

To enable others skilled in the art so fully to comprehend the underlying features thereof that they may embody the same by any of the numerous modifications in composition and method contemplated by this 95 invention, the following description will outline the principles and rules to be observed.

As a result of exhaustive experiments, I have discovered and am enabled to cure two 100 primary difficulties in the prevailing methods of imitating embossed work. That is to say, I have found first, that by employing proper ingredients the ultimate composition of the raised characters will be comparatively flexible instead of being hard and 105

brittle, and second that the composition may be caused to adhere much more tenaciously to the paper than is the case with the current methods. In the prevailing methods, 5 the base of the character is first laid by blending it with ordinary stiff printers'-ink. By ordinary printers'-ink is meant an ink of the general type represented by the following formula or variations thereof, to 10 wit: 68% heavy linseed oil varnish, 7% Japan drier, 19% carbon black, and 6% Prussian blue. On this quick-drying base is then applied the usual resinous composition, which is subsequently fused in place. 15 Heretofore, it has not been observed that an incompatibility subsists between the ordinary printers'-ink and the resinous material used, under the conditions in which they are blended, and as a consequence the ultimate 20 printed character has not been perfectly composed or constituted.

I have discovered that, by selecting an ink free from certain of the conventional ingredients and physical characteristics of ordinary stiff printing ink, and by selecting a 25 compatible composition, and by properly blending the same, that an entirely different character is obtained which is at once comparatively flexible and which will adhere 30 most tenaciously to the paper. I have found that certain ingredients characteristically composing ordinary printers'-ink exercise a harmful effect. That is to say, ordinary stiff printers'-ink, among other things, contains 35 material quantities of "drying" and of strong varnish-producing ingredients so that, from a theoretical aspect, ordinary printers'-ink may simply be regarded as a sort of quick-drying varnish. The reason 40 for this lies in the fact that for all ordinary purposes it is highly desirable for the ink to take the form of a hard film almost immediately after leaving press so that it will not "offset" or "smudge" during subsequent 45 manipulations. This immediate "set" is obtained by the agency of varnish-producing and "drying" ingredients and, in fact, a typical varnish is sometimes added to the other ingredients in making the ink. 50 For example, a typical printing ink would more or less closely conform to the above-mentioned formula. My experiments have demonstrated, however, that the drying and varnish producing ingredients so desirable 55 for ordinary stiff printers'-ink exercises a harmful effect when it is attempted to manipulate a printed character with the reliefing or embossing compound. That is to say, these ingredients are not sufficiently compatible with the fusible gum and they tend to impair the tenacity of adhesion and to render the gum brittle when applied to the paper.

In practising this invention, the ink 60 should contain a sufficient amount of oily

material, such as linseed oil or glycerin, to superficially penetrate the paper and amalgamate with the fusible gum, and the ink should possess greater fluidity than the ordinary tacky printers'-ink; *i. e.*, it should be 70 sufficiently fluid almost to flow from its receptacle. An ink suitable for this purpose may be composed of 73% of boiled linseed oil, 8% of rosin, (as distinguished from a true drying agent), 12% of carbon black, 75 and 6% of Prussian blue. It will be observed that this formula is characteristically different from the constituents of ordinary printers'-ink and when it is used in connection with a suitable fusible gum, especially 80 of animal origin such as that hereinafter proposed, it will be found to be entirely compatible therewith and to produce a character that at once is flexible and yet adheres tenaciously to the paper immediately after 85 leaving the printing press and melting oven. Another typical composition such as may be successfully used in accordance with this method could contain 1½ lbs. of glycerin as a vehicle, 1 lb. of dextrin as a body, and 90 ¼ lb. of anilin color, and, by varying the amount of glycerin, the different weather conditions will be met.

My investigations have further developed a superior species of gum which will render 95 much more satisfactory results than the gums heretofore employed with ordinary printers'-ink. That is to say, if ordinary shellac is freed from the limy, waxy substances and other foreign ingredients, so that substantially pure shellac or refined shellac is obtained, this product when powdered will be preëminently compatible with either of the typical inks above mentioned and it will, when fused in place, immediately after leaving the printing press, produce a character at once flexible and strongly adherent to the paper.

By using the ingredients herein specified and by completing the method immediately 11 after leaving the printing press, it will be found that the cold sheets of printed matter may be stacked at once without danger of sticking together and they may be folded like an ordinary letter-head without chipping or flaking.

Without further analysis, the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should 12 and are intended to be comprehended within the meaning and range of equivalency of the following claims.

Having thus revealed this invention, I claim as new and desire to secure the fol- 13

lowing combinations of elements, or equivalents thereof, by Letters Patent of the United States:—

1. A process for producing raised flexible printing which comprehends printing a flat character by means of a slow-drying ink containing a considerable amount of an oily ingredient; and immediately thereafter applying pulverulent refined shellac; and then 10 fusing the shellac in place.
2. An article of manufacture of the nature disclosed, consisting of a sheet of paper having a flexible raised character tenaciously adhering thereto, said character being composed of refined shellac; and an ink 15 substantially free from a varnish drier.
3. A process of making raised flexible printing, which comprehends printing a flat character by means of an ink substantially free from a varnish drier; and then fusing 20 powdered shellac upon said character to cause it to amalgamate therewith.
4. An article of manufacture of the nature disclosed, consisting of a sheet of paper having a flexible printed character adhering 25 tenaciously thereto and composed of refined shellac; and a base of ink substantially free from quick-setting varnishing elements.
5. A process of the nature disclosed for 30 producing raised printing, which compe-

hends printing a flat character by means of an ink containing glycerin; and then fusing a gum of animal origin on said character.

6. A process of the nature disclosed for 35 producing raised printing, which comprehends printing a flat character by means of an ink containing dextrin and an oily agent, and then fusing powdered shellac on said character.

7. A process of the nature disclosed for 40 producing raised printing, which comprehends printing a flat character by means of a slow-setting partially fluid ink; and then fusing a gum of animal origin on said 45 character.

8. An article of manufacture consisting of a sheet of hard-surfaced paper provided with printed letters elevated in imitation of embossed printing and consisting of a fused compound composed of a shellac-like gum 50 blended into a water soluble ink containing coloring matter and a hygroscopic agent.

In witness whereof, I hereunto subscribe my name, as attested by the two subscribing witnesses.

SAMUEL LIPSIUS.
